ENLARGING EASEL

Frederick B. Jensen, Sacramento, Calif.

Application April 6, 1945, Serial No. 586,889

4 Claims. (Cl. 88—24)

1

This invention relates to enlarging easels for photographic work, and more particularly to an easel adapted for making one or more exposures on a single sheet of photographic paper.

A main object of this invention is to provide an improved enlarging easel of simple construction adapted to facilitate the printing of a single exposure or of a plurality of exposures on a single sheet of printing paper, and wherein handling of the printing paper is minimized during the various stages of processing.

Further objects and advantages of the invention will appear from the following description and claims, and from the accompanying drawings, wherein:

Figure 1 is a plan view of an enlarging easel according to this invention with a portion of the top cover broken away to show the interior structure.

Figure 2 is a cross-sectional view taken on line 2—2 of Figure 1.

Figure 3 is a front elevational view of the enlarging easel of Figure 1 with the cover in raised position.

Figure 4 is a cross-sectional view taken on line 4—4 of Figure 1.

Figure 5 is a perspective view of the paper holder employed in the easel of Figure 1.

Figure 6 is a bottom view of one of a plurality of printing masks employed with the enlarging easel of Figure 1.

Referring to the drawings, 1 designates a shallow rectangular tray member forming the bottom portion of the easel. Said tray member comprises a rectangular base 2 provided with side walls 3, 3' and a rear wall 4. Hinged to rear wall 4 is a rectangular top cover 5 adapted to extend from side to side of tray member 1, and terminating at a front edge spaced a short distance inwardly from the front edge of base 2. A rear rib 6 is secured to the rear edge of rear wall 4 which acts as a stop means to limit the rotation of cover 5 around its hinges and to support said cover at times in a raised position substantially perpendicular to tray 1, as shown in Figure 3.

Cover 5 is formed with an aperture adapted to receive one of a plurality of rectangular printing masks 7 in a position perpendicular to the front edge of the cover. The bottom edges of the aperture are rabbeted to receive metal supporting strips 8 which are secured to said edges and extend inwardly with respect to the aperture. The edges of each mask 7 are also rabbeted to cooperate with the inwardly extending edges of strips 8 for supporting the mask with its bottom sur-

2

face substantially flush with the bottom surface of cover 5. As shown in the drawings, the aperture for each mask 7 is normally arranged so that the mask is positioned perpendicular to the front edge of the cover. However, a removable section 9 is provided in the cover, as shown in Figure 3, which may be taken out, and replaced at the top portion of the aperture, as viewed in Figure 3, for converting the aperture for use in 10 making horizontal single prints of the size of the aperture.

Slidably mounted within tray 1 is a rectangular paper holder 10 comprising a rigid board provided with a resilient leaf spring clip member 11 appropriately mounted adjacent the rear edge of holder 10 on a rib member 12 secured at said rear edge. A tab member 13 is secured adjacent the front edge of holder 10. Said holder 10 is adapted to be slidably positioned within tray 1 20 with its rear edge abutting rear wall 4 and with tab member 13 protruding beyond the front edge of cover 5 so that paper holder 10 may be slid laterally in tray 1 by manual actuation of tab member 13. A standard sheet of printing paper may 25 be clamped to holder 10 by engaging one edge thereof under clip member 11. A guide strip 25 at one lateral edge of holder 10 is provided for properly positioning the paper.

Side wall 3 terminates about midway between the front and rear edges of tray 1. A series of stop members 14, 15 and 16 are pivotally secured adjacent the side edges of base 2 and are normally in alignment with wall 3. A resilient strip 17 of metal or other suitable material is secured to the side edge of base 2 and said stop members are adapted to normally contact said strip at their longitudinal surfaces, as shown in Figure 1. Each stop member may be rotated to an inwardly projecting position normal to strip 17, 30 said strip cooperating with the end surfaces of said stop members to resiliently secure them in projecting position when thus rotated. The stop members are of different lengths and are adapted 35 to cooperate with paper holder 10 to act as a lateral limiting means for properly positioning paper holder 10 for printing through masks having different sizes or locations of mask apertures to secure the most economical utilization 40 of a standard sheet of printing paper with a given mask.

In operation, a standard sheet of printing paper is mounted on holder 10, a desired mask is positioned in the aperture of cover 5, and an appropriate stop member 14, 15 or 16 is rotated 55 to inwardly projecting position. Holder 10 is

moved into abutment with said stop member and the printing operation is performed. Holder 10 is then moved into abutment with side wall 3' and another print is made. The two prints will be separated by an appropriate blank margin.

For the mask shown at 7 in the drawings the stop members need not be employed inasmuch as aperture 19 in said mask is so positioned that a first exposure may be made with the left edge of holder 10 in abutment with side wall 3 and a second exposure may be made with the right edge of holder 10 in abutment with side wall 3'. The two prints thus made will be separated by the desired blank margin.

While a specific embodiment of an enlarging easel has been disclosed in the foregoing description, it will be understood that various modifications within the spirit of the invention may occur to those skilled in the art. Therefore, it is intended that no limitations be placed on the invention other than as defined by the scope of the appended claims.

What is claimed is:

1. An easel for photographic printing comprising a shallow horizontal trough member, a cover member hinged to said trough member at a rear wall thereof, an aperture in said cover member, said aperture being formed and arranged to receive and support a printing mask therein, a horizontal paper holder slidably positioned within said trough member, and a plurality of stop arms of different lengths pivotally connected to said trough member at a side portion thereof and adapted to be rotated to an inwardly projecting position in said trough member in the plane of said paper holder to position said paper holder for printing successive exposures through a mask supported in said aperture onto a sheet of printing paper held on said paper holder responsive to successive sliding movements of said paper holder.

2. An easel for photographic printing comprising a shallow horizontal trough member, a cover member hinged to said trough member at a rear wall thereof, an aperture in said cover member, said aperture being formed and arranged to receive and support a printing mask therein, a horizontal paper holder slidably positioned within said trough member, and a plurality of stop arms of different lengths pivotally connected to said trough member at a side portion thereof and adapted to be rotated to an inwardly projecting position in said trough member in the plane of said paper holder to position said paper holder for printing successive exposures through a mask supported in said aperture onto a sheet of printing paper held on said paper holder responsive to successive sliding movements of said paper holder, and a spring clip member mounted on said paper holder adjacent one edge thereof adapted to resiliently secure said sheet of printing paper to said paper holder.

3. An easel for photographic printing comprising a shallow, generally rectangular, horizontal trough member, a cover member for said trough member hinged to said trough member

at a rear wall thereof and adapted to extend over said trough member, the front edge of said cover member being positioned a short distance inwardly of the front edge of said trough member, an aperture in said cover member, said aperture being formed and arranged to receive and support a printing mask therein, a horizontal paper holder slidably positioned within said trough member for lateral movement therein and formed with a rear edge adapted to slidably abut the rear wall of said trough member and having a front portion extending forwardly beyond the front edge of said cover member, and a plurality of stop arms of different lengths pivotally connected to said trough member at a side portion thereof, each of said stop arms being adapted to be rotated to an inwardly projecting position in said trough member in the plane of said paper holder to successively position said paper holder responsive to lateral movement thereof for printing successive exposures through a mask supported in said aperture onto a sheet of printing paper held on said paper holder.

25 4. An easel for photographic printing comprising a shallow generally rectangular horizontal trough member, a cover member for said trough member hinged to said trough member at a rear wall thereof and adapted to extend over said trough member, the front edge of said cover member being positioned a short distance inwardly of the front edge of said trough member, an aperture in said cover member, said aperture being formed and arranged to receive and support a printing mask therein, a horizontal paper holder slidably positioned within said trough member for lateral movement therein and formed with a rear edge adapted to slidably abut the rear wall of said trough member and having a front portion extending forwardly beyond the front edge of said cover member, a plurality of stop arms of different lengths pivotally connected to said trough member at a side portion thereof, each of said stop arms being adapted to be rotated to an inwardly projecting position in said trough member in the plane of said paper holder to successively position said paper holder responsive to lateral movements thereof for printing successive exposures through a mask supported in said aperture onto a sheet of printing paper held on said paper holder, and spring means provided for holding said stop arms in inwardly projecting position.
